UNITED STATES PATENT OFFICE.

GEORGE H. DAVIS, OF WORCESTER, MASSACHUSETTS.

COIN-OPERATED SIGNALING DEVICE.

1,150,254.

Specification of Letters Patent. Patented Aug. 17, 1915.

Application filed March 5, 1910. Serial No. 547,530.

To all whom it may concern:

Be it known that I, GEORGE H. DAVIS, a citizen of the United States, residing at Worcester, in the county of Worcester and State of Massachusetts, have invented a new and useful Coin-Operated Signaling Device, of which the following is a specification.

The object of this invention is to provide a new and improved coin operated signaling device which, while adapted for other uses, is especially adapted for use in connection with a telephone.

The coin operated signaling devices now employed with telephones usually have a different receiving slot for each coin; that is, a receiving slot for a twenty-five cent piece, a receiving slot for a ten cent piece, and a receiving slot for a five cent piece. A great deal of confusion occurs in connection with this device by the user putting the wrong coin in a slot; that is, the user is apt to put a five or ten cent piece in the twenty-five cent slot, or a ten cent piece in the twenty-five cent slot. This does not properly operate the signal and in some instances clogs the device.

The object of my invention is to overcome this difficulty. To do this I arrange the device so as to have a single slot adapted for receiving the different sized coins and combine a selecting device which will select and differently direct the coin of different sizes, and a plurality of signaling devices therewith, so that coins of different sizes may be inserted in the same slot and each particular coin will be directed to operate its particular signaling device. In the preferred form of the device, the coins are received from the single slot in a run-way which has switching devices coöperating therewith, whereby the different sized coins will be selected and differently directed, and a plurality of chutes is arranged in connection with the run-way and switching devices to receive the differently directed coins, and signaling devices are arranged for coöperation with the chutes. The signaling devices are preferably arranged to coöperate with all but one of the chutes. Thus by properly designing the mechanism as hereinafter described, the difficulty above mentioned is overcome.

The slot is made large enough to receive a twenty-five cent piece and obviously it will take any other smaller sized coin. The

twenty-five cent pieces, ten cent pieces and five cent pieces are selected and directed to different chutes; and as they pass from their respective chutes, they will operate the signaling devices arranged in connection with each chute so that the value of the coin inserted will be indicated by the signaling device. The device is also arranged so that a Canadian or silver five cent piece will be directed into the same chute or passage-way as the United States nickel five cent piece. The selecting mechanism is also arranged to direct a one cent piece into a chute which does not have any signaling device coöperating therewith, so that the insertion of a one cent piece or penny will not operate the signaling device. The chutes preferably deliver all the coins into a receiving box. This box may have a back or side locked thereto and the box itself is locked in position. By this arrangement, the coins may be removed by the inspector unlocking and removing the box and then unlocking the back or side and taking the coins out, or the lock which holds the back or side in position may be a lock which cannot be opened by the inspector so that the inspector will remove the box and insert an empty one. The box has a slot for receiving the coins, which slot may be provided with any usual retaining device for preventing the coins from being shaken out of the box.

The slot into which all the coins are inserted is constructed as hereinafter described so as to prevent flipping of the coins into the device and so as to prevent the introducing of one coin so close after another as to cause confusion in the signaling. The receiving mouth of the run-way is also constructed so that all the coins will pass down the run-way under similar conditions. By this arrangement, a very efficient device for the purposes stated is provided.

One embodiment of the invention is shown in the accompanying two sheets of drawings in which,

Figure 1 is a front elevation of the complete device. Fig. 2 is a side elevation thereof. Fig. 3 is a rear elevation. Fig. 4 is a plan view of the coin receiving box. Fig. 5 is a rear sectional elevation on an enlarged scale, the section being taken on line 5-5 of Fig. 2. Fig. 6 is a front elevation of the run-way and switching mechanism, the same being turned to stand in a vertical

plane instead of in its normal inclined position. Fig. 6^a is a section taken on the line 6^a—6^a of Fig. 6 illustrating the operation with a Canadian or with a silver five cent piece. Fig. 7 is a rear elevation of the chutes. Fig. 8 is a side elevation of the same. Fig. 9 is a sectional elevation through the run-way and switches taken on line 9—9 of Fig. 6. Fig. 10 is a view illustrating the operation of one of the switches. Fig. 11 is a view illustrating the mouth of the run-way, and Fig. 12 is a view of the gong or signaling device used in connection with the twenty-five cent piece chute.

15 The device will be best understood by a detailed description thereof. The device is arranged in a suitable frame or shell A, which may be made out of plates bent and riveted together. The back B of the frame 20 is made removable so that the device can be inspected and the back may be held to the frame by suitable lugs and a key. The back may be provided with an extension so that the device may be secured in place on 25 the wall, or any other means for holding the device in an upright position can be employed.

The device is provided with a coin-receiving slot S. This slot can be arranged at any 30 point but preferably is arranged in a dome or cup 10 extending up from the top of the shell so that the slot S will be arranged horizontally and the coin will have to be inserted in the position shown in Fig. 11. 35 The slot S is made just wide enough to receive a twenty-five cent piece. The slot is made curved in shape, as shown in Fig. 5, and the dome 10 is provided with a lip 100 which projects downwardly so that the coin 40 will have to be tilted as it is inserted. This makes it necessary that the coins be inserted one at a time and prevents two coins being inserted together or closely after each other. This construction is adopted to prevent any 45 confusion in the signaling.

Arranged diagonally across the shell is a run-way R which has a mouth 11 projecting up into the dome or cup 10 to receive the coins as they are inserted in the slot S. This 50 run-way is arranged, as shown in Fig. 5, and in cross section in Fig. 9, and the same is provided with suitable feet by which it can be secured in position. The receiving mouth 11 of the run-way is made flaring and S-shaped so that the coins will all strike on the point or edge 110 which will direct all the coins down into the run-way under practically the same conditions so that the coins 55 will have about the same speed down the run-way, no matter how quickly or slowly they are inserted into the slot S.

The bottom wall of the run-way is provided with three openings 12, 13, and 14 and these openings are guarded or partly covered by switches or trap doors 15, 16, and 17.

Each of these switches is provided with bent ears 18 which fit between bent ears 19 on the floor or bottom side of the run-way so that by employing pins or pintles 20 the switches will be pivoted. Each switch is provided with an arm 21 extending toward the run-way or mouth 11, which arm is turned down at the edge near the end and has a cam edge 22. These arms normally rest against the bottom or floor of the run-way. As the center of gravity of each switch or trap door is to the right of the pintles, as shown in Fig. 6, the switches will remain by gravity in the position shown so that they practically will form part of the bottom or floor of the run-way. The arms of the three switches are arranged in different positions. The arm of the switch 15 is arranged so that a twenty-five cent piece will engage the same and so that the other coins will clear the same. The arm of the switch 16 is arranged so that a five cent piece will engage the same but a ten cent piece and a one cent piece will clear the same. The arm of the switch 17 is arranged so that a one cent piece will engage the same but so that a ten cent piece will clear the same.

As a coin passes down the run-way and as it engages the cam face on an arm of a switch, the coin will lift the switch or trap door and the particular coin engaging the arm will be directed out through the particular opening controlled by the switch or trap door. Thus a twenty-five cent piece will be directed down through the opening 100 12; a five cent piece will be directed down through the opening 13; a one cent piece will be directed down through the opening 14; while a ten cent piece will pass through the entire run-way without engaging any of the arms of the switches or trap doors and will pass out of the mouth 23 at the end of the run-way.

The partition or wall in the bottom of the run-way between the holes 12 and 13 is bent downward and has a directing ear 131, and the hole 13 is cut away so that an opening 130 is provided just front of the switch or trap door 16. This opening is of a size so that a Canadian or a silver five cent piece will drop down through the same, as shown in Fig. 6^a, and will not slide down over the face of the switch or trap door 16. The body of the preceding switch 15 or trap door 110 150 is bent so as to have a directing surface 150 in line with the bent down portion of said partition so that this bent down or depressed portion 150 of the switch 15 will direct the Canadian or silver five cent pieces properly 120 in line with the opening 130, the depression 125 to accommodate the Canadian or silver five cent pieces thus commencing on the front or leading edge of the trap door 15 and extending to a point in the floor of the run-way under the trap door 16. This arrangement 130

is such that a Canadian or silver five cent piece will drop at the same point as the United States nickel five cent piece and will operate the same signal.

5 The switches are provided with bosses 230 so as to prevent any coin striking a pin or pintle 20 and thus clogging the device. The run-way R may have ears punched and turned out of the same so as to leave orifices, as shown in Fig. 5, in the back of the run-way so that the switches or trap doors can be inspected when the back of the frame is removed. These ears also serve to protect the cams from being deranged when 15 the run-way is being constructed, handled and placed in position.

The run-way and the switches form a selecting device for selecting the different sized coins and differently directing the 20 same and this selecting device is arranged to coöperate with a plurality of chutes or passage-ways C. These chutes may be formed by two pieces of metal properly stamped and secured to a central piece or 25 plate and the chutes may be secured in position by suitable screws. Arranged under the opening 12 in the run-way is the chute or passage-way 24, which chute has a wide mouth or hopper 240, as shown in Fig. 8. 30 Arranged under the opening 13 is a chute or passage-way 25 which has a wide mouth or receiving opening 250. This chute 25 is made curved in shape, as indicated in Fig. 5. Arranged under the opening 14 is a chute or 35 passage-way 26 which has a wide mouth or hopper 260. Arranged in connection with the end or mouth of the run-way R is a chute or passage-way 27 which leads into the end of the chute 25. The chute 24 which 40 receives the twenty-five cent pieces from the opening 12 is made L-shaped and at its corner is cut away or opened out, and arranged in position to coöperate therewith is a gong G which will be struck by the twenty-five 45 cent piece as it passes down the chute 24. The chute 24 merges with the chute 26 and the two chutes 24 and 26 have an outlet or mouth 28.

It will be seen that the cent pieces or pennies which pass out from the openings 14 in the run-way through the chute 26 will pass directly to the outlet 28 without encountering or striking any signaling device.

The chute 27 for the ten cent pieces is 50 made L-shaped and the same is cut away at its corner so that the ten cent piece passing down the same will project through the cut-away portion and strike on the top of a bell H which is arranged to coöperate therewith. The ten cent piece will then run into the chute 25 for the five cent pieces and this chute is arranged so that its outlet 29 will direct the descending coin on the inside of the said bell H. Thus the ten cent piece in 55 its passage through the chute 27 and the

chute 25 will strike the bell H twice with some little interval of time between the blows and thus the bell will be rung twice for a ten cent piece. A five cent piece will merely pass down the chute 25 and will 70 strike the bell H once. This operation will take place with a United States nickel five cent piece which is selected and directed downward by the switch 16 or by a Canadian, or by a silver five cent piece which will drop down through the opening 130. Therefore, all five cent coins will be directed into the same chute 25. Thus a twenty-five cent piece will ring the gong G, a ten cent piece will ring the bell H twice, a five cent piece will ring the bell H once, and a one cent piece will pass directly through the chutes without operating any of the signaling devices. By this arrangement any coin put into the receiving slot S will only operate 80 its proper signaling device.

The outlet 28 for the chutes 24 and 26 and the outlet 29 for the chute 25 are arranged side by side and just over a slot 30 in a removable box D which is inserted in the bottom of the frame. The removable box is provided with a removable side or back 32 which is held in place by a lock 33. The removable box D is held in position by a lock 34. When it is desired to remove the 90 coins, the lock 34 is released so that the removable box D can be drawn out of the frame A and an empty box is inserted, or if the inspector is allowed to remove the coins, the lock 33 is operated by him so that the box can be opened by removing or turning down the removable back or side 32 and the coins removed. Thus a very simple device for the purpose described is provided, as the same is made largely of sheet metal 95 which can be cheaply manufactured in quantity by stamping and the same is easy and simple to manufacture.

While the device is particularly adapted for use in connection with telephones, of course the same may be put to other uses. While the device has been described for use in connection with a particular system of coins, it is obvious, of course, that by properly designing the parts, the same can be 110 made to handle any system of coins, such as coins commonly employed in other countries.

The details and arrangements herein shown and described may be greatly varied by a skilled mechanic without departing from the scope of my invention as expressed in the claims. Therefore I do not wish to be limited to the particular details of construction shown and described, but 120

What I do claim is:

1. In a coin operated signaling device, the combination of a member having a slot for receiving different sized coins, a selecting device for selecting and differently di- 130

recting coins of different sizes, a chute co-operating therewith having two passage-ways on one side and two passage-ways on the other side, which passage-ways lead 5 to outlets side by side, one of said passage-ways being cut away, a gong arranged in connection with this cut-away portion, another of said passage-ways being cut away, a bell arranged to be struck by the coin 10 passing down the same, this passage-way communicating with the third passage-way which has its outlet arranged to have coins passing down the same strike the inside of the bell, and a fourth passage-way communicating with the first named passageway beyond the cutaway portion so that coins passing down the same will not ring either the gong or the bell.

2. In a coin operated signaling device, 20 the combination of a member having a slot for receiving different sized coins, a selecting device for selecting and differently directing coins of different sizes, a plurality of chutes 24, 25, 26 and 27 co-operating 25 therewith, a gong, the first chute 24 being cut away so that coins passing down the same will ring the gong, a bell, the second chute 25 being arranged so that coins passing down the same will strike the bell, the 30 third chute 27 being arranged so that coins passing down the same will strike the bell and then pass into second chute 25 and again strike the bell, and the fourth chute 26 being connected to the first chute 24 beyond 35 the gong so that coins passing down the same will not strike either the gong or the bell.

3. In a coin operated signaling device, the combination of a member having a slot

for receiving twenty-five cent and smaller 40 coins, a selecting device for selecting and differently directing coins of different sizes, including means for directing the United 45 States and Canadian five cent coins in the same path, four chutes for receiving the differently directed coins, signaling devices adapted to be struck by coins descending the chutes into which the twenty-five, ten and five cent pieces are directed, and a chute in which the one cent pieces are directed, which has no signaling device. 50

4. In a coin operated signal device, the combination of a casing having a slot at its upper end for receiving different sized 55 coins, a run-way positioned to receive the coins from said slot, having openings along its length for discharging the different coins at different points, two chutes 24 and 25 arranged adjacent to each other and depending from different openings in the runway, two additional chutes 26 and 27 arranged to receive coins from the remaining 60 openings and to discharge them respectively into the aforesaid chutes 24 and 25, which latter chutes 24 and 25 have their discharge ends brought to a common point, a signal for the chute 24, another signal common to the chutes 25 and 27, and a coin receptacle positioned below the discharge 65 ends of said chutes 24 and 25, for the purpose set forth.

In testimony whereof I have hereunto set my hand, in the presence of two subscribing witnesses.

GEORGE H. DAVIS.
